(57) **CLAIM**

The ornamental design for a combined fish cleaner grate and tray, as shown and described.

DESCRIPTION

FIG. 1 is a top view of the grate shown removed from the tray for clarity of disclosure, showing my new design;

FIG. 2 is a front elevation view of the grate, wherein rear elevation view is identical to front view, thereof;

FIG. 3 is an end elevation view of the grate, wherein each end is identical, thereof;

FIG. 4 is a bottom view of the grate thereof;

FIG. 5 is a perspective view of the grate thereof;

FIG. 6 is a top view of the tray shown removed from the grate for clarity of disclosure, showing my new design

FIG. 7 is a front elevation view of the tray, wherein rear elevation view is identical to front view, thereof;

FIG. 8 is an end elevation view of the tray, wherein each end is identical, thereof;

FIG. 9 is a bottom view of the tray thereof;

FIG. 10 is a perspective view of the tray thereof;

FIG. 11 is a perspective view of the combined fish cleaner grate and tray showing the grate fitted into the tray thereof;

FIG. 12 is an exploded view showing grate separated from tray thereof;

FIG. 13 is a cross sectional view taken in the direction of line 13-13 of FIG. 11; and,

FIG. 14 is an enlarged cross sectional view taken from FIG. 13.
